UNITED STATES PATENT OFFICE

CHARLES H. ROLLASON, OF WHEELING, WEST VIRGINIA, ASSIGNEE TO WHEELING STEEL CORPORATION, OF WHEELING, WEST VIRGINIA, A CORPORATION OF DELAWARE

NONREFILLABLE CONTAINER

Application filed April 3, 1929. Serial No. 352,218.

This invention relates to sheet metal containers, and more particularly to covers for such containers.

The primary object of the invention is to provide a container for oils, greases, and the like, which is so constructed that, after removal of the contents, re-filling and re-sealing of the container is prevented.

In describing the invention in detail, reference is herein had to the accompanying drawings, in which—

Figure 1 is a top plan view of the invention;

Figure 2 is a section on line 2—2, Fig. 1; and—

Figure 3 is an enlarged fragmentary sectional detail view.

Referring to said drawings, the reference numeral 1 designates a sheet metal can or drum having a head 2 provided with a removable cover 3. The head 2 is seamed to the body 1 in the usual manner, as indicated at 4, and is provided with a central opening defined by an outwardly extending neck flange 5, the margin of which is rolled or curled outwardly to form a bead 6, the bead being disposed in spaced relation to the head 2. A ring 7 is provided which has an annular base 8, the latter being of substantially L-shape in cross section. The base 8 of the ring is designed to seat on the head 2 and to be engaged between the latter and the bead 6.

It will be understood in this respect that in manufacture the ring 7 is positioned as shown in Fig. 3 of the drawings, following which the bead 6 is rolled outwardly. The bead 6 is thus of a diameter greater than that of the inner circumference of the base 8 of the ring, consequently, the ring must be secured in the position shown in Fig. 3 at the time of manufacture of the container.

The cover 3 is provided with a flange 9, said flange fitting within the flange 5 of the head 2 and being curled outwardly and downward, as shown at 10, to lie in encircling relation to and over the bead 6, and within the confines of the ring 7. If desired, a suitable gasket 11 may be employed which seats

on the bead 6 and is engaged by the outwardly turned portion 10 of the flange 9.

After the can has been filled, the cover is applied, following which the flange 7 is rolled inwardly to overlie and engage the rolled portion 10, thereby securing the cover in position. The ring 7 is formed of sheet metal having a horizontal tongue 12 on its base in order that the projection 11 can be gripped and the ring 7 torn or stripped from its position, thereby enabling the cover to be removed.

From the foregoing, it will be seen that the ring 7 is applied by the manufacturer and that the packer turns the upper edge of the ring inwardly to secure the cover in position after the can has been filled. Consequently, after the ring 7 has been stripped from its position, it is impossible for a new ring to be inserted in position due to the fact that the bead 6 is of greater diameter than the inner circumference of the base 8 of the ring. In other words, the ring must be applied at the time of manufacture and, therefore, a new ring cannot be introduced in place after the original ring has been stripped or removed from the container head.

What is claimed is—

1. A container comprising a head having therein a circular opening defined by an upstanding neck flange which is turned outwardly to form a terminal bead, a bendable ring including an upright body portion and an inwardly directed base flange, said body portion being disposed in encircling spaced relation to said bead and said base portion being immovably held between said bead and the head, and a sheet metal cover receivable within the embrace of said neck flange and having an outwardly turned annular rim for seating in embracing overlying relation to said bead, said ring having its upper edge portion adapted to be bent inwardly into overlying holding relation to said cover rim.

2. A container comprising a head having therein a circular opening defined by an upstanding neck flange which is turned outwardly to form a terminal bead, a ring including an upright body portion and an inwardly directed base flange, said body por-

tion being disposed in encircling spaced relation to said bead and said base portion being immovably held between said bead and the head, and a cover receivable within the embrace of said neck flange and having an outwardly turned annular rim for seating in overlying relation to said bead and having its terminal edge receivable in closely fitted position between said bead and the body portion 10 of said ring, said ring having its upper edge portion adapted to be rolled inwardly into overlying holding relation to said cover rim.

3. A container having a head provided with an opening defined by an upstanding 15 neck flange which has its top portion turned outwardly to form a roll-like bead, a frangible sheet metal ring disposed in encircling relation to said bead, said ring having an inwardly directed base flange gripped between the under side of said bead and said head, a cover embodying an upright annular portion having its upper edge curled outward to form a rim adapted for seating in overlying relation to said bead, said ring 20 having its upper edge portion adapted to be turned inward from its normal upstanding position into overlying seated relation to said cover rim and being adapted to be broken and stripped from the container head to 25 permit removal of the cover.

In testimony whereof, I affix my signature.
CHARLES H. ROLLASON.
